ERNEST E. SCHMID, DECEASED, LATE OF HOLLIS, NEW YORK, BY CHLORITA SCOFIELD SCHMID, EXECUTRIX, OF HOLLIS, NEW YORK, AND WILLIAM H. SCHNEIDER, OF FREEPORT, NEW YORK.

SPLICE BAR.

Application filed June 9, 1927. Serial No. 197,556.

This invention relates to a splice bar for third rails of electric railways particularly designed for third rails of T bar construction.

5 The usual method of joining the T bars or T rails forming the third rail of an electric railway is by means of two splicing bars, one on each side of the rail and bolted together, the bolts passing thru the holes in 10 the T bar or rails and the splicing bars. The bars usually fish part of the under side of the top flange of the T and in addition thereto, contact with the sides of the web of the bar by means of projections on the fish 15 plates. If the bolts remain tight the joint holds, but if one of these bars becomes loose due to loose bolts and the natural wear between the parts every time a contact shoe passes over, the joint frees itself from the 20 fishing surface and permits both horizontal and vertical movement of the T thereby throwing the running surface of the T bar or rail out of alignment. This enables the third rail contact shoe which rides the running surface of the T to strike the high T 25 bar at the joint and if the shoes do not break, it often produces a blow of sufficient strength to cause over-turning of the third rail.

It is, therefore, the principal object of this 30 invention to provide a one piece, double splice bar that will rigidly and permanently retain the adjoining ends of the T bars in the same vertical position to present a smooth running surface for a contact shoe.

35 It is another object of this invention to provide a single piece double splice bar for railway rail joints that will permit the horizontal movement due to changes in temperature but will prevent any vertical movement.

40 It is still another object of this invention to provide a more economical and more effective splice bar for T rails that will be easier to apply and will be more permanent in character.

45 It is still another object of this invention to provide a splice bar for an inverted T bar in which the adjoining rail ends will be resiliently supported in a relatively uniform vertical position.

50 Another object of this invention is to provide a unitary splice bar for the adjoining ends of a railway rail in which all of the side parts are relatively clear from falling objects,

Further objects and advantages of the invention will appear in the following description of the attached drawings which illustrate one preferred form of embodiment to which the invention is adaptable, and in 60 which—

Fig. 1 is a vertical section thru the T rail and an improved splice bar substantially on the line 1—1 of Fig. 2.

Fig. 2 is a side elevation of a splice bar 65 showing its adaptation to the adjoining ends of T rails.

Fig. 3 is a detail view of the elongated slot in the splice bar.

Fig. 4 is a vertical section similar to Fig. 70 1 but showing a modified form of clamping means.

The common T rail 10 is particularly adapted for use in connection with the third rail electric systems to conduct electrical current for electric railways because of the 75 large contact surface provided at low cost. As is well known in commercial practice, the railway vehicle is provided with a contact shoe which rides on the surface of this 80 T rail and completes the circuit for the operating motors. As shown in Fig. 2 the adjoining ends 10^a and 10^b of similar rails are clamped on each side by the single piece, 85 double clamp or splice bar 12 which forms the substance of this invention.

The clamp or splice bar 12 as shown in Fig. 1 is substantially U shaped in vertical section with the upper ends 12^a flared over to receive the flange of the T bar 10 and 90 act as a shoulder therefor. The side portions 12^b closely embrace the web of the T and are perforated as at 14 to correspond with perforations 10^b in the web. The perforations in the splice bar 12 may be elliptical 95 in shape as shown in Fig. 3 in order to permit the necessary longitudinal expansion and contraction of the rail 10 due to changes in temperatures and to take the ordinary track bolt 16. This bolt is provided with a 100 lock washer 17 and a nut 18 screw threaded thereon and passes thru the corresponding apertures in the splice bar and rail. When tightened it will permanently and rigidly retain the clamping bar to the rail.

105 It will thus be obvious that with the necessary bolts properly tightened in the adjoining ends of the T bar 10 and thru the clamping bar 12, the ends of the rail will be held in permanent position. The flared ends 12^a of 110

the clamping bar 12 will directly support the ends of the T rails in the same relative height and the resilient portion 12^c joining the bottom of the side portions 12^b being enlarged 5 and spaced from the bottom of the T rail will act as a cushion and absorb substantially all of the sudden shocks caused by the contact shoe (not shown) on the railway car.

If one of the bolts should become loose, the 10 clamping action due to the spring effect of the outwardly flared sides 12^a which are so bent that when drawn inward, they exert a clamping and wedging action, would be sufficient to maintain a secure joint. If all the 15 bolts should become loosened, the most extreme condition, the rails 10^a and 10^b could drop only to the intermediate portion 12^c of the clamps which is normally located about 1/16" below the bottom of the rails. No 20 harmful result will occur. It is to be understood that the portion 12^c is only depressed enough to provide easy attachment and assembly of the splice bar, leaving only a minimum clearance below the bottom of the rails. 25 Such construction permits such extreme conditions of one rail dropping to the depressed portion 12^c without substantially affecting the vertical position of the rail end and thus not interfering with the contact of the contact 30 shoes.

The round headed track bolt 16 provided with shoulders to engage cooperating parts in the splice bar is used to prevent the turning of the head when the nut 18 is tightened as 35 shown in Fig. 1. However, a slight modification of the splice bar 22 as shown in Fig. 4 in which the side portion 22^b is formed by pressing to receive the square headed machine bolt 26, will prevent rotation of the head 40 when the nut 28 is tightened.

As will be noted from an inspection of either Figs. 1 or 4, if the contact shoe (not shown) breaks, and should drop from the side of the T rail 10 it will drop clear and will not 45 come in contact with the support or the splice bar or be obstructed in any other way, thus preventing short circuits or overturned third rails or other accidents which disrupt electric railway service.

50 One of the advantages of the single piece U shaped double splice bar besides affording quick and ready attachment to the T rail, is that it permits a lighter material to be used. This is due to the fact that the lower upset 55 portion 12^c of the splice bar 12 strengthens the section and it also acts as a resilient cushion as before mentioned. The space between the end of the web and the top of the portion 12^c permits vertical expansion of the rail as the 60 elliptical bolt holes allow horizontal expansion. The splice bar is preferably constructed as a sheet metal stamping and galvanized to resist corrosion, being of one piece it is easily slipped over the bottom leg of the T rail 65 and may be secured in place by one man

whereas the ordinary double two-pieced splice bar needs the services of two men to efficiently make a splice.

From the foregoing detailed description, it is clear that a highly improved splice bar is 70 provided in which the parts will not become dislodged, will permit changes in length of the rail due to the elliptical bolt holes, will support the adjoining rail heads in the same plane, will permit the use of square headed 75 machine bolts by preventing the heads turning, will prevent the common accidents due to variations in height of the adjoining rail ends and will not obstruct the contact shoes which frequently break off in service, thus vastly 80 improving third rail operating conditions.

While there has been disclosed a particular form of splice bar for a rail joint to which the invention is especially adapted, it is to be understood that the same type of splice bar may 85 be applied to T rails and that the invention is not to be limited to these specific details and, therefore, protection is desired on the broad scope and spirit of the invention as described herein and as claimed in the claims 90 appended hereto.

What is claimed is:

1. In a rail joint of the class described, in combination with the adjoining ends of two inverted T rails, a one piece reversely bent 95 splice bar closely embracing the flange and web portions of the rail to prevent vertical movement of the rail ends, and securing means extending through said splice bar and rails.

2. In a rail joint of the class described, in combination with the adjoining ends of two inverted T rails, a single sheet metal splice bar closely embracing the lower portion of the flange and the web of said rails to prevent 100 vertical movement and means to prevent excessive longitudinal movement thereof.

3. In a rail joint of the class described, in combination with the adjoining ends of two rails, a U-shaped splice bar having splice bolts 105 therein, the upper ends of said bar being adapted to closely embrace the lower side of the flange and the fillets, the intermediate portion of the splice bar being disposed slightly below the base of the rails to prevent 110 vertical misalignment of the splice bar due to looseness of the splice bolts, said splice bar adapted to be confined within the horizontal projections of the rail.

4. In a rail joint of the class described in combination with the adjoining ends of inverted T rails, a U shaped splice bar to clampingly embrace the web and under flange of the rail, the connecting portion of the clamp being depressed below the bottom of the web 120 to afford a resilient and reinforcing connection and one of the side portions being offset to prevent rotation of the connecting bolts. 125

5. In a rail joint of the class described, in combination with a pair of adjoining rail 130

- ends, a **U** shaped sheet metal splice bar to retain the ends together, the said splice bar being provided with elliptical holes in the sides thereof to permit changes in length of the 5 rails due to changes in temperature and to prevent the common track bolts from turning.
6. In rail joint of the class described, in combination with a pair of adjoining **T** rail 10 ends, one piece **U** shaped sheet metal splice bar to permanently clamp the sections together and means to tighten said splice bar, said means being held from rotation by square shoulders positively held, the splice 15 bar being shaped to the rail to leave an unobstructed side exposed to a contact shoe.
7. A splice bar for electric third rails, comprising a one piece **U** shaped sheet metal member with the legs of the **U** shaped to conform 20 to the under portion of the head and the sides of the rail, and the base of the **U** resiliently connecting the legs together.
8. A sheet metal splice bar for electric third 25 **T** rails, comprising a pair of side plates adapted to contact with the sides and head of the rail, bolt holes through the side bars adapted to register with the holes in the rail, and an integral sheet metal portion to extend underneath the rail connecting the side plates into 30 a unitary structure.
9. A sheet metal splice bar for electric third 35 **T** rails, comprising a pair of side plates adapted to contact with the sides and head of the rail, bolt holes through the side bars adapted to register with the holes in the rail, means to prevent bolts passed through said 40 holes from turning when a nut is tightened thereon, and an integral sheet metal portion to extend underneath the rail connecting the side plates into a unitary structure.
10. An article of manufacture for third 45 rails, comprising a one piece sheet metal splice bar of **U** shape, the sides of the **U** embracing the rail and the intermediate portion being enlarged and depressed below the web of said rail sufficient to permit assembly and entirely within the vertical projections of the rail, said splice bar being adapted to slip transversely onto said rails.
11. An article of manufacture for electric 50 third rails comprising a one piece sheet metal **U** shaped splice bar, the sides of which are adapted to closely embrace a rail and the intermediate portion of which reinforces the bar and resiliently connects the sides. 55
12. In a rail joint of the class described, in combination with the adjoining ends of two inverted **T** rails, a single sheet metal splice bar closely embracing the lower portion of the web portion of said rails to prevent vertical 60 movement thereof and positive means to prevent excessive longitudinal movement of said rail ends.
13. In a rail joint of the class described in combination with the adjoining ends of two 65 rails, a **U**-shaped splice bar, having splice bolts therein, said bar being adapted to closely embrace the lower portion of the web of said rails, and to be supported by said rails, the intermediate portion of the splice bar being disposed slightly below the base of the rails to prevent vertical misalignment thereof.
14. A splice bar for electric third rails, comprising a one-piece **U**-shaped sheet metal 70 member with the legs thereof shaped to conform to the sides of the rail and the base of the **U** resiliently connecting the legs together.
15. A sheet metal splice bar for electric 75 third **T**-rails comprising a pair of side plates adapted to extend closely adjacent and in contact with the sides of the web portion of the rail, the side bars being provided with holes adapted to register with the holes in the rail, means to prevent bolts passed through 80 said holes from turning when a nut is tightened thereon and an integral sheet metal portion adapted to extend underneath the rail 85 connecting the side plates to form a unitary structure. 90
